UNITED STATES PATENT OFFICE.

JESSE M. SAID, OF CORNING, NEW YORK, ASSIGNOR TO CORNING GLASS WORKS, OF CORNING, NEW YORK, A CORPORATION OF NEW YORK.

WATER-COOLED SHIELD FOR TANK-FURNACES.

1,360,587.

Specification of Letters Patent. Patented Nov. 30, 1920.

Application filed January 2, 1920. Serial No. 349,109.

To all whom it may concern:

Be it known that I, JESSE M. SAID, a citizen of the United States of America, and a resident of Corning, county of Steuben, 5 State of New York, have invented certain new and useful Improvements in Water-Cooled Shields for Tank-Furnaces, of which the following is a specification.

This invention relates to a water-cooled 10 shield for tank furnaces.

Glass tank furnaces are usually provided with a series of boot-openings, arranged in the curtain walls of the furnace, at intervals, for the purpose of gathering molten glass 15 therefrom. These openings are usually made from two to three feet high and about two feet wide, for the purpose of inserting and removing the boots from the tank.

It has been the practice heretofore to provide the boot-openings with shields for the protection of the gatherer, the shields commonly used consisting of plates of sheet-iron so placed in front of the boot-opening that an opening is left large enough to permit the 25 insertion of the gathering iron into the tank and its withdrawal with a gather thereon.

The sheet-iron shields quickly become so heated that the radiation therefrom is sufficiently great to render it difficult for the men 30 to continuously gather from the openings. I have discovered that by placing a wire screen carrying a water film in front of the sheet-metal shield, the heat radiated by the sheet-metal shield is absorbed and the men 35 protected.

In the exemplification of my invention to be hereinafter fully described and claimed, I have shown a form of device which has been thoroughly tested in a glass factory manufacturing articles from glass requiring a 40 very high temperature, viz, 2500° to 3000° F., to place it in a workable condition. Due to this high temperature, the workmen had found it difficult to make gathers from the 45 tanks for any length of time, as the heat transmitted through the boot-opening was such that they were soon overcome. However, with my apparatus in place, the workmen are not at all affected, and, in fact, no 50 appreciable amount of heat is transmitted to the outside of the screen.

In the accompanying drawings,

Figure 1, illustrates a view of a glass tank furnace boot-opening with a shield embodying my invention in operative position, and

Figs. 2, 3, 4, 5 and 6, are detail sections taken on the lines 2—2, 3—3, 4—4, 5—5 and 6—6, respectively, of Fig. 1.

In the drawings, the boot-opening in the curtain wall, 1, is closed by a sheet metal plate, 3, having its two opposite vertical edges bent outwardly, as shown at 4. The size of the plate, 3, is such that it overlaps the boot-opening on three sides. Suitably secured to the upper edge of the plate is a 65 normally horizontal water-pipe, 5, having a series of perforations, 6, which extend substantially the entire length thereof, and are for the purpose of directing a stream of water in the form of a fine spray outwardly 70 and at nearly right angles to the shield, 3. Encircling the water-pipe, 5, is a hood, 7, in the form of an inverted J having an inner curved edge, 7a, fastened to the top of the plate, 3. The front of the hood, 7, extends downwardly and inwardly toward the plate, 3, and terminates a suitable distance from such plate, so that a gap, preferably say of one inch, is left between the lower edge of the hood and the front face of the 80 plate.

Positioned in front of the plate, 3, is a screen, 8, of wire netting of free mesh, which is of an area corresponding approximately to the area of the plate, 3. The screen, 8, at 85 its top, is bent slightly inward and is secured to the plate, 3, between the inner edge of the hood and the plate. A horizontal strip of screening, 9, rests against the outer edge of the hood, 7, and extends down along the 90 outer face of the screen, 8, having its lower edge secured to the latter by means of the wire loops, 10. Except where the screen, 8, has its upper edge secured to the plate, 3, it is spaced therefrom.

The plate, 3, is shown as provided with two openings, 11, and, 12, the former being for the purpose of enabling the workman to make gathers, while the latter is for the purpose of permitting an auxiliary gas jet 100 to project a flame into the boot-opening. The openings, 11, and, 12, are similarly formed, so a description of one will do for both. In cutting the sheet, 3, to form an opening, I prefer to bend the vertical edges 13, to the V form shown in Fig. 2. To the top edges, 14, of an opening, are preferably secured V-shaped plates, 15, which, together with the vertical V-shaped edges, 13, form troughs, the purpose of which will 110

be hereinafter more fully described. The screen, 8, is secured to the edges, 13, and plates, 15.

For the purpose of enabling a workman to carry the apparatus, I provide the handles, 16, which are secured to the plate 3, by means of bolts, 17. To keep the screen spaced from the plate, 3, where the handles are secured to the latter by the bolts, 17, are the nuts, 18, which are interposed between the screen and the plate. Thus, the bolts, 17, serve the purpose as securing means for the outer edges of the screen, as well as securing means for the handles, 16.

When the apparatus is set up in position in front of the boot-opening of a furnace, the pipe, 5, is connected to a water supply line and water under pressure admitted thereto. The water passes through the opening, 6, of the pipe, 5, in form of spray which strikes the hood, 7, and is deflected thereby downwardly against the screen, 8. It then trickles down the screen, 8, forming a water film thereon. As the screen is spaced from the plate, 3, in its entirety, the water does not strike the plate in its passage down the screen. What water passes down the screen above the openings, 11, and, 12, is deflected by the troughs, 15, and, 13, as will be understood. As the heat is more intense around these openings, it will be apparent that the water collected by the troughs will tend to reduce this heat somewhat.

In actual practice, while the temperature within the boot-openings is about 3000 degrees F., the temperature of the water is increased very little on its passage down the screen. In fact, the screen can be touched

by the hand at any place on its area, and it is cold to the touch. Should the screen, 8, be removed, however, and the water allowed to flow down the surface of the plate, 3, it at once turns to steam and is evaporated. I, therefore, believe that the success of my apparatus lies in the fact that the screen is spaced from the plate, and the volume of water passing downwardly thereover is kept from contact with the plate, although the heat radiated by the plate is absorbed by the curtain of water which I have provided.

What I claim, and desire to secure by Letters Patent is:

1. In combination with a boot-opening of a tank, of means for intercepting heat radiation therefrom, comprising a film netting screen positioned in front of said boot-opening, and carrying a water film.

2. Means for cooling a boot-opening of a tank, comprising a plate partially closing said opening, and a screen spaced in front of said plate and carrying a water film.

3. Means for cooling a boot-opening of a tank, comprising a plate partially closing said opening, a screen in front of said plate and carrying a water film, and means for spacing said screen from said plate.

4. Means for cooling a boot-opening of a tank, comprising a plate partially closing said opening, a screen in front of said plate and carrying a water film, and means for spacing said screen from said plate, said spacing means forming a part of manipulating handles.

In testimony whereof I hereunto sign my name this 30 day of Dec., 1919.

JESSE M. SAID.
